R. B. LOWE

DISPLAY RACK

Filed April 6, 1925

Fig. 2.

Inventor

Richard B. Lowe

by *Dwight & Hague, Atty's.*

UNITED STATES PATENT OFFICE.

RICHARD BARRETT LOWE, OF MADISON, SOUTH DAKOTA.

DISPLAY RACK.

Application filed April 6, 1925. Serial No. 21,140.

The object of my invention is to provide a display rack of simple, durable and inexpensive construction, which is especially designed to be used for the purpose of displaying sample goods, such as congoleum and linoleum rugs and the like, in such a manner that a large number of samples may be supported in a comparatively small space, and so constructed and arranged that any one of the samples may be moved to position whereby it may be supported in a vertical position where it may be easily seen by the customer.

A further object is to provide a display rack for the purpose above described, which may be easily and quickly dissembled for the purpose of shipping in a small and compact package.

A further object is to provide a display rack which is especially adapted to support heavy composition rugs, such as linoleum or congoleum.

My invention consists in the construction, arrangement and combination of the various parts of the device, whereby the objects contemplated are attained, as herein-after more fully set forth, pointed out in my claims, and illustrated in the accompanying drawings, in which:

Figure 1 is a top view of my improved device.

Figure 2 is a front view of the same.

Figure 3 is a perspective view of one of the pivot plates.

Figure 4 is a detail sectional view taken on the line 4-4 of Figure 1.

Figure 5 is a detail sectional view taken on the line 5-5 of Figure 2.

Figure 6 is a detail sectional view taken on the line 6-6 of Figure 2.

My improved device comprises a supporting member 10 designed to be supported in a vertical position, with one face against the outer face of a wall. The member 10 is provided with openings 11 for the purpose of receiving screws by means of which the said support is secured in position. Running transversely across the front face of the member 10 near its top is an angle iron 12 secured in position by means of bolts or rivets 13, one face of the angle being adjacent to the member 10 while the other member is mounted perpendicular therewith. The perpendicular member is provided with a series of pivot openings 14 which are spaced equidistant apart.

Near the bottom end of the member 10 is a similar angle iron 15 mounted in an inverted position from the member 12 and provided with a stop lug 15^a. In each of the openings 14 of the member 12 I have provided a brace rod 16 which has a vertically arranged member 17 which extend through the said opening 14, said members 17 being secured in position by means of cotter keys 18. The body portion of the member 16 extends downwardly and outwardly, as clearly shown in Figure 2.

The lower end of each of the rods 16 is provided with a flattened portion 19 which is provided with an opening to receive a small bolt 20. The openings 14 of the member 15 are provided with a series of vertically arranged pivot pins 21, the upper end of each of which is provided with a cotter key 22. The lower end of each of the pins 21 is provided with a strap iron 23 which has one end formed with a loop 24 designed to surround the pin 21. The body portion 23 enters the said loop in a tangent manner so that the center of the pivot 21 will rest in a plane a slight distance from the inner face of the member 23. The upper edge of the member 23 is provided with a laterally extending flange 25, see Figure 6. The depth of the said flange is considerably greater than the thickness of the material to be supported.

The member 23 is provided with a series of bolts 26 designed to enter the upper edge of the sample 28. A clamp plate 29 is provided for the outer face of the upper edge of the sample 28, and is provided with openings 30 for receiving bolts 26, the openings being so located that the upper edge of the member 29 will rest adjacent and beneath the lower face of the member 25. The nuts 31 are provided for the bolts 26. By this means the sample 28 may be rigidly connected with the member 23. The outer end of each of the bars 23 is supported by the outer and lower end of a corresponding rod 16, the bolt 20 being placed through the outer one of the openings 30.

The spacing between the openings 14 is such that the members 23 may be folded to a position substantially parallel with the member 10 with the outer ones adjacent to the lug 15^a, and when in said position the bars 23 will be substantially parallel and adjacent to each other. It will be seen that when placed in this position, if two or more

of the samples are swung together to a position, say at right angles to their initial position, it will be seen that as they are swung from the first position to the second, the body portion of the members 23 will have a slightly longitudinal movement relative to each other. This would cause the nut of the bolt 20 to engage the end of the member 19 and a swinging movement would thereby be prevented. To overcome this difficulty I have formed a bulged portion 32 in each of the bars 29 near its outer end, the bulged portion being provided with inclined ends 33 which will cause the two adjacent bars 23 to swing outwardly from each other by the lower end of the member 19 engaging said inclined portion 32 as said members 23 are moved longitudinally with each other.

Thus it will be seen that I have provided a display rack of simple, durable and inexpensive construction, which may be easily and quickly knocked down by simply removing the cotter keys 18 and 22, and the bolt 20. The rods 16, the base 10 and the members 23 may then be stacked in a bundle and bound together and shipped in said knocked down compact position. It will further be seen that the device may be easily and quickly assembled.

30 A further advantage of my construction lies in the fact that the supporting bar 23 may be detached from the angular plates 12 and 15 and the bolts 26 and 30 removed, which may then be used as a templet for 35 punching the holes in the upper edge of the linoleum sample, by simply laying the said linoleum sample on a suitable support such as a block of wood, and then placing the bar 23 on the upper surface of said sample 40 with the flange 25 adjacent to the upper edge of the sample, said flange serving as a guide for easily and quickly alining the plate 23, after which the bolt holes in said plate 23 may be used for receiving the punch and 45 thereby insuring the proper spacing of the punched holes. The openings of all of said bars being the same distance apart, so that one bar may be used to punch the holes for all of the samples, after which the said bar 50 may again be placed in position on the rack.

I claim as my invention:

1. A display rack comprising a supporting member, a pair of angle irons adjacent to one face of said support and parallel 55 with each other, each of which is provided

with a laterally extending portion, each of said laterally extending portions being provided with a series of pivot openings, a brace rod for each of the openings of one of said angles, a supporting bar having a pivot 60 member for each of the openings of the other one of said angles, said bars being arranged in a horizontal position, the outer end of which is supported by said brace rods, the upper edge of said bar being provided with 65 a laterally extending flange, a series of bolts for said bar, a detachable clamping plate carried by said bolts and mounted parallel with said bar and having its upper edge adjacent to the said flange.

2. A display rack comprising a supporting member, a pair of angle irons adjacent to one face of said support and parallel with each other, each of which is provided with a laterally extending portion, each of said laterally extending portions being provided with a series of pivot openings, a brace rod for each of the openings of one of said angles, a supporting bar having a pivot member 70 for each of the openings of the other one of said angles, said bars being arranged in a horizontal position, the outer end of which is supported by said brace rods, the upper edge of said bar being provided with 75 a laterally extending flange, a series of bolts for said bar, a detachable clamping plate carried by said bolts and mounted parallel with said bar and having its upper edge adjacent to the said flange, the outer end of each of said clamp members being provided 80 with an outwardly bulged portion.

3. In a device of the class described, a support, a series of horizontally arranged supporting bars pivoted to said support, said bars being mounted close together and 85 designed to swing in a common plane, means for supporting the outer end of each of said bars, means for supporting a sample from each of said bars, said bar supporting means and said sample supporting means each including transversely arranged bolts having 90 projecting ends, means carried by each of said bars for preventing the projecting ends of the bolts of one of said bars from engaging the projecting ends of the bolts of an adjacent bar due to their longitudinal movement relative to each other as the said bars are swung in a common plane.

RICHARD BARRETT LOWE,
